[57] CLAIM

The ornamental design for a loudspeaker cabinet, as shown and described.

DESCRIPTION

FIG. 1 is a perspective view of a loudspeaker cabinet of the present invention;

FIG. 2 is a front elevational view thereof;

FIG. 3 is a left side elevational view thereof;

FIG. 4 is a rear elevational view thereof;

FIG. 5 is a top plan view thereof;

FIG. 6 is a right side elevational view thereof; and,

FIG. 7 is a bottom plan view thereof.

The broken line representation of the speakers, horns and vents in FIGS. 1, 2, 3 and 4 and stand mount in FIG. 7 are for purposes of illustration only and form no part of the claimed design.
